US0D1007673S

(12) **United States Design Patent** (10) **Patent No.:** **US D1,007,673 S**
(45) **Date of Patent:** **** Dec. 12, 2023**

(54) **INFUSION PUMP WITH RECHARGEABLE BATTERY**

(71) Applicants: **Baxter International Inc.**, Deerfield, IL (US); **Baxter Healthcare SA**, Glattpark (CH)

(72) Inventors: **Jiri Slaby**, Buffalo Grove, IL (US); **Kevin Boron**, Chicago, IL (US); **Partha Chandrakant**, Hawthorn Woods, IL (US); **Robert Cuevas**, Twin Lakes, WI (US); **Mark Luzbetak**, Kildeer, IL (US); **Steve Pippin**, Libertyville, IL (US); **Raymond Kan**, Lake Forest, IL (US); **Paul Duncan**, Northfield, IL (US)

(73) Assignees: **Baxter International Inc.**, Deerfield, IL (US); **Baxter Healthcare SA**, Glattpark (CH)

(**) Term: **15 Years**

(21) Appl. No.: **29/854,527**

(22) Filed: **Sep. 26, 2022**

(57) **CLAIM**

The ornamental design for an infusion pump with rechargeable battery, as shown and described herein.

DESCRIPTION

FIG. 1 illustrates a front-perspective view of an infusion pump with a rechargeable battery.

FIG. 2 illustrates a front view of the infusion pump.

FIG. 3 illustrates a rear view of the infusion pump.

FIG. 4 illustrates a left-side view of the infusion pump.

FIG. 5 illustrates a right-side view of the infusion pump.

FIG. 6 illustrates a top-plan view of the infusion pump; and, FIG. 7 illustrates a bottom-up view of the infusion pump. The broken lines shown in the drawings illustrate portions of the infusion pump and form no part of the claimed design.

1 Claim, 7 Drawing Sheets
